1

The present invention concerns electronic calculating machines and more particularly to mechanisms for translating the results delivered by such machines.

The object of the invention is to provide mechanism adapted to receive the output of a calculating machine and automatically to transfer a curve translating the output onto a sensitive paper, as successive points, the ordinates of the curve being supplied by the calculating machine.

Mechanism embodying the invention comprises substantially an electronic totalizer, with a capacity $(B^n - 1)$, B being the basis of the numeration system according to which the machine operates, a totalizer connected to the outlet of the machine for registering the results delivered by the latter as impulses, a rotating registering cylinder provided with a driving motor, and capable of receiving, on its outer surface, a sensitive paper, a cylindrical drum, fast with the registering cylinder, a part of the lateral peripheral surface of which is constituted by a surface having alternately translucent and opaque areas, the number of the translucent areas of which is B^n , and the remainder of the lateral peripheral surface of which is constituted by an opaque surface, and a luminous supply source and a photo-electric cell arranged opposite each other, at fixed points, on either side of the wall of the drum, said photo-electric cell being connected, through an impulse generator-amplifier, with the totalizer, so that the impulses transmitted by the generator-amplifier are added to the impulses issued from the machine to the totalizer, the output of the last stage of the totalizer being connected to means arranged to impress the sensitive paper on the registering cylinder each time an output impulse is transmitted by the totalizer, said means being arranged on a support designed for parallel displacement in relation with the axis of the registering cylinder by a constant amount for each revolution turn of the latter, means being provided for rotating the registering cylinder and limiting said rotation to one turn each time a result is supplied by the machine to the totalizer, and for resetting the totalizer to zero position at the end of each revolution of the registering cylinder.

The means to impress the sensitive paper on the registering drum may consist, for example, of an electric luminous supply source such as a fixed spark gap or a bulb filled with an inert gas, in which case the sensitive paper may be a photographic paper. The supply source is connected to the output of the totalizer through a member or means such as a thyratron, capable of deliver-

2

ing a discharge current to the supply source, and an optical system is provided for projecting the image of the supply source onto the sensitive paper. The paper may also be an electrolytic paper of a known kind adapted to be marked by an electrode, and the printing means may comprise an electrode arranged to rub on the paper.

The support for the printing means may consist of a carriage connected by a nut or the like to a rotatable threaded rod extending parallel with the axis of the registering cylinder and being connected with the shaft of the latter by a gear or system of gears.

For setting the registering cylinder into rotation, and limiting said rotation to one turn, means may be provided for controlling the motor itself, such means being of a known type capable of being actuated through an impulse delivered by the machine. A one revolution clutch of any known type may also be used, being inserted between the motor and the shaft of the registering cylinder, said clutch being controlled by a relay actuated by an impulse generated by the machine.

To reset the totalizer to zero, an opaque disc or similar element is keyed on the shaft of the registering cylinder and is provided with a window, the angular position of which is the same as that of the opaque surface constituting part of the impulse control drum fast with the registering cylinder, a luminous supply source and a photo-electric cell being arranged, facing each other on either side of this disc, at fixed points, and the cell being connected, through a pulse generator-amplifier to means for resetting the totalizer to zero. For this purpose, a device controlled by the output impulse issued from the totalizer may be arranged for interrupting the connection between the totalizer and the impulse generator-amplifier connected to the photo-electric cell cooperating with the above mentioned drum.

The invention will be hereafter described in greater detail with reference to the accompanying drawing, in which:

Fig. 1 is a diagrammatic and schematic view showing a preferred embodiment of the invention, suitable for use in connection with a machine operating in the binary system.

Fig. 2 is a detailed perspective view, showing a drum controlling the impulses and a zero resetting control disc.

As shown diagrammatically in Fig. 1, the illustrative device or mechanism comprises a registering cylinder 1, carrying a photo-sensitive paper 2, and the shaft 3 of which is connected with the shaft of an electric driving motor 4. On the shaft

3 of cylinder 1, is keyed a gear pinion 5 meshing with a gear 6, itself keyed on a threaded rod 7, adapted upon being rotated to effect linear movement of a carriage 8 provided with a fixed spark gap 9 and an optical system 10 adapted to project, on to the paper 2, the image of the spark passing between the balls of the spark gap 9.

On the shaft 3 is also keyed a drum 11, a part of the lateral peripheral surface of which (Fig. 2) is constituted by a cinematographic film provided with a series of black lines 12, regularly spaced and leaving between them transparent intervals 13, in number 2^n . These lines 12 and intervals 13 only fill one part of the periphery of the drum 11, the remainder of this periphery consisting of an opaque area 14. Inside the drum 11, is arranged a fixed bulb 15, cooperating through the transparent intervals 13 in the peripheral wall of the drum with a photo-electric cell 16.

On the other end of shaft 3 is keyed an opaque disc 17 comprising a window 18 (Fig. 2), the angular position of which corresponds to that of the opaque area 14 of the drum 11. On either side of this disc are arranged, at fixed points, a bulb 19 and a photo-electric cell 20.

Arranged at the outlet of the electronic mathematical machine, shown diagrammatically at 21, is a binary electronic totalizer 22, of a type known per se, with a capacity (2^n-1) and designed for receiving the calculation results issued by the machine 21. The totalizer 22 is also connected to an impulse generator-amplifier 23, controlled by cell 16, the connection between the generator 23 and the totalizer 22 being so arranged that the impulses from said generator 23 are added to those from the machine 21.

The output from the last stage of the totalizer 22 is connected through a thyratron 24 with the spark gap 9, whereas the photo-electric cell 20 is connected with an impulse generator-amplifier 25, itself connected with the zero re-setting mechanism of the totalizer 22.

A device 26, of a known kind per se, is arranged to effect a single revolution of the motor 4 in response to generation of a particular impulse by the calculating machine 21 immediately after the transfer of a result from the machine 21 to the totalizer 22.

The operation of such a device will now be described, assuming, for simplicity's sake, that the curve to be recorded has only positive ordinates between 0 and (2^n-1) .

The ordinate N to be recorded, expressed by impulses in the binary numeration system, is transferred by the machine 21 to the totalizer 22. This transfer is accompanied, as above indicated, by a particular impulse which acts through the device 26 to effect a single revolution of the motor 4. The cylinder 1 is thus driven in rotation, the gears 5 and 6 rotating the threaded rod 7 which causes the displacement of the carriage 8 carrying the spark gap 9. The pitch of the screw thread on the rod 7 is such that, for example, a displacement of 1 mm. of the carriage corresponds to one revolution of the cylinder.

Drum 11 rotates at the same time as the cylinder 1 and this rotation causes the passing, between bulb 15 and the cell 16, of the strips 12 and 13, alternately opaque and translucent. The keying of the drum 11 is such that when the first translucent interval 13, following the opaque section 14, passes in front of bulb 15, it actuates the cylinder, starting its rotation. The alternation of opaque and translucent strips causes the

generation, by cell 16, of impulses which are amplified and transformed into short impulses by generator 23, these pulses being added to the number N registered in the totalizer. When the latter has received 2^n-N impulses, corresponding to the passing of 2^n-N strips 13 between the bulb 15 and the cell 16, and to a corresponding angle of rotation of the cylinder 1 with its sensitive paper 2, the totalizer 22 is filled, passes again through zero, and generates an output impulse which, actuating thyratron 24, causes the discharge of a spark across the spark gap 9. The discharge spark, focussed by the optical system 10, impresses the paper 2 on which a point becomes recorded, said point being at a distance proportional to 2^n-N from the cylinder generatrix corresponding to the appearance of the first impulse issued from cell 16.

As cylinder 1 and drum 11 continue their rotation, the cell 16 continues the generation of impulses which are registered in the totalizer 22 without causing new discharges since the number of these impulses is necessarily less than 2^n . When the opaque area 14 comes between bulb 15 and the cell 16, the latter stops generating impulses. At this time the window 18 of the disc 17 comes between bulb 19 and the cell 20, and the latter generates an impulse which, transformed by the generator-amplifier 25, causes the zeroizing of the totalizer 22 which is then ready to receive a new result from the machine, after which, the cylinder 1 having completed one revolution, the motor 4 stops.

A new result is transmitted to the totalizer 22 by the machine 21, all the previous operations are resumed, and a new point is recorded on the paper 2, and so on. The curve 27 is thus traced, point by point, materializing under the form $2^n-y(x)$, and the results $y(x)$ delivered by the machine 21. The curve $y(x)$ may in this way be obtained by just suitably drawing the X axis on the paper 2.

The device according to the invention makes it possible, in every case in which the results of a calculation performed by the machine 21 may be translated into a curve, to check the operation of the machine and to find out the errors it may have made. Any error will be shown, during the tracing of the curve by the recording of a point definitely outside the normal tracing to be expected, or by an abnormal, sudden discontinuity of said tracing.

What I claim is:

1. The combination with an electronic calculating machine capable of delivering calculated results by impulses, of a device for tracing curves relative to the calculations performed by said machine and comprising: an electronic stage totalizer of a capacity of (B^n-1) , B being the basis of the numeration system according to which said machine operates, means connecting said electronic totalizer to said machine for receiving the output of said machine for registering the results delivered by said machine as impulses, a rotative registering cylinder, a sensitive paper on an external surface of said registering cylinder, a driving motor for said registering cylinder, a cylindrical drum fast with said registering cylinder, the lateral surface of said drum being constituted on one part of its periphery with a surface presenting alternatively translucent and opaque sections, said translucent sections being number B^n , the remaining part of the periphery of said lateral surface of said drum presenting an opaque surface, a luminous

supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, means connected to the output of the last stage of said totalizer and arranged to impress said sensitive paper every time that an output impulse is delivered by said totalizer, a support for said means arranged for displacement in a direction parallel to the axis of said registering cylinder and a constant amount for each rotation of said registering cylinder, means to control and limit to one turn the rotation of said registering cylinder each time a result is supplied by said machine to said totalizer, and means for zeroizing said totalizer at the end of each revolution of said registering cylinder.

2. The combination with an electronic calculating machine capable of delivering calculated results by impulses, of a device for tracing curves relative to the calculations performed by said machine and comprising: an electronic stage totalizer of a capacity of $(B^n - 1)$, B being the basis of the numeration system according to which said machine operates, means connecting said electronic totalizer to said machine for receiving the output of said machine for registering the results delivered by said machine as impulses, a rotative registering cylinder, a sensitive paper on the external surface of said registering cylinder, a driving motor for said registering cylinder, a cylindrical drum fast with said registering cylinder, the lateral surface of said drum being constituted, on one part of its periphery with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, an electric luminous source, means connecting said electric luminous source to said totalizer and including a device for supplying a discharge current to said electric luminous source every time an output impulse is delivered by said totalizer, an optical device for projecting the image of said luminous source onto said sensitive paper for forming an impression on said paper, a support for said electric luminous source mounted for displacement, in a direction parallel to the axis of said registering cylinder, and a constant amount for each rotation of said registering cylinder, means to control and limit to one turn the rotation of said registering cylinder each time a result is supplied by said machine to said totalizer, and means for zeroizing said totalizer at the end of each revolution of said registering cylinder.

3. The combination with an electronic calculating machine capable of delivering calculated results by impulses, of a device for tracing curves relative to the calculations performed by said machine and comprising: an electronic stage totalizer of a capacity of $(B^n - 1)$, B being the basis of the numeration system according to which said machine operates, means connecting

said electronic totalizer to said machine for receiving the output of said machine for registering the results delivered by said machine as impulses, a rotative registering cylinder, a photographic paper on the external surface of said registering cylinder, a driving motor for said registering cylinder, a cylindrical drum fast with said registering cylinder, the lateral surface of said drum being constituted, on one part of its periphery with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, a spark gap, means connecting said spark gap to said totalizer and including a thyratron for supplying a discharge current to said spark gap every time an output impulse is delivered by said totalizer, an optical device arranged for projecting the image supplied by said spark gap onto said sensitive paper for forming an impression on said paper, a support for said spark gap mounted for displacement, in a direction parallel to the axis of said registering cylinder, and a constant amount for each rotation of said registering cylinder, means to control and limit to one turn the rotation of said registering cylinder each time a result is supplied by said machine to said totalizer, and means for zeroizing said totalizer at the end of each revolution of said registering cylinder.

4. The combination with an electronic calculating machine capable of delivering calculated results by impulses, of a device for tracing curves relative to the calculations performed by said machine and comprising: an electronic stage totalizer of a capacity of $(B^n - 1)$, B being the basis of the numeration system according to which said machine operates, means connecting said electronic totalizer to said machine for receiving the output of said machine for registering the results delivered by said machine as impulses, a rotative registering cylinder, a photographic paper on the external surface of said registering cylinder, a driving motor for said registering cylinder, a cylindrical drum fast with said registering cylinder, the lateral surface of said drum being constituted on one part of its periphery with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, a bulb filled with inert gas, means connecting said bulb to said totalizer and including a thyratron for supplying a current to said bulb every time an output impulse is delivered by said totalizer, an optical device for projecting the image supplied by said bulb onto said sensitive paper for forming an impression on said paper, a support for said bulb mounted for dis-

placement, in a direction parallel to the axis of said registering cylinder, and a constant amount for each rotation of said registering cylinder, means to control and limit to one turn the rotation of said registering cylinder each time a result is supplied by said machine to said totalizer, and means for zeroizing said totalizer at the end of each revolution of said registering cylinder.

5. The combination with an electronic calculating machine capable of delivering calculated results by impulses, of a device for tracing curves relative to the calculations performed by said machine and comprising: an electronic stage totalizer of a capacity of (B^n-1) , B being the basis of the numeration system according to which said machine operates, means connecting said electronic totalizer to said machine for receiving the output of said machine for registering the results delivered by said machine as impulses, a rotative registering cylinder, an electrolytic paper wound on said registering cylinder, a driving motor for said registering cylinder, a cylindrical drum fast with said registering cylinder, the lateral surface of said drum being constituted on one part of its periphery, with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, an electrode cooperating with said electrolytic paper wound around said registering cylinder and being connected to the output of the last stage of said totalizer to impress said sensitive paper every time that an output impulse is delivered by said totalizer, a support for said electrode mounted for displacement, in a direction parallel to the axis of said registering cylinder, and a constant amount for each rotation of said registering cylinder, means to control and limit to one turn the rotation of said registering cylinder, each time a result is supplied by said machine to said totalizer, and means for zeroizing said totalizer at the end of each revolution of said registering cylinder.

6. The combination with an electronic calculating machine capable of delivering calculated results by impulses, of a device for tracing curves relative to the calculations performed by said machine and comprising: an electronic stage totalizer of a capacity of (B^n-1) , B being the basis of the numeration system according to which said machine operates, means connecting said electronic totalizer to said machine for receiving the output of said machine for registering the results delivered by said machine as impulses, a rotative registering cylinder, a sensitive paper on the external surface of said registering cylinder, a driving motor for said registering cylinder, a cylindrical drum fast with said registering cylinder, the lateral surface of said drum being constituted on one part of its periphery with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, means connected to the output of the last stage of said totalizer and being operable thereby to impress said sensitive paper every time that an output impulse is delivered by said totalizer, a support for said means mounted for displacement, in a direction parallel to the axis of said registering cylinder, and a constant amount for each rotation of said registering cylinder, an electronic device controlled by an impulse delivered by said machine for controlling the rotation of said registering cylinder by said motor and for limiting said rotation to one turn, and means for zeroizing said totalizer at the end of each revolution of said registering cylinder.

other and being respectively in fixed locations, on either side of the wall of said drum, an amplifier-generator of impulses so connecting said photoelectric cell with said totalizer that the impulses generated by the amplifier-generator are added to said impulses delivered by said machine to said totalizer, means connected to the output of the last stage of said totalizer and being operable thereby to impress said sensitive paper every time that an output impulse is delivered by said totalizer, a threaded rod parallel to the axis of said registering cylinder, a carrier, a connecting member linking said carrier to said threaded rod, at least one gear connecting 10 said threaded rod to the shaft of said registering cylinder, means to control and limit to one turn the rotation of said registering cylinder each time a result is supplied by said machine to said totalizer, and means for zeroizing said totalizer at the end of each revolution of said registering cylinder.

15. The combination with an electronic calculating machine capable of delivering calculated results by impulses, of a device for tracing curves relative to the calculations performed by said machine and comprising: an electronic stage totalizer of a capacity of (B^n-1) , B being the basis of the numeration system according to which said machine operates, means connecting said electronic totalizer to said machine for receiving the output of said machine for registering the results delivered by said machine as impulses, a rotative registering cylinder, a sensitive paper on the external surface of said registering cylinder, a driving motor for said registering cylinder, a cylindrical drum fast with said registering cylinder, the lateral surface of said drum being constituted on one part of its periphery with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, 20 means connected to the output of the last stage of said totalizer and being operable thereby to impress said sensitive paper every time that an output impulse is delivered by said totalizer, a support for said means mounted for displacement, in a direction parallel to the axis of said registering cylinder, and a constant amount for each rotation of said registering cylinder, an electronic device controlled by an impulse delivered by said machine for controlling the rotation of said registering cylinder by said motor and for limiting said rotation to one turn, and means for zeroizing said totalizer at the end of each revolution of said registering cylinder.

25. The combination with an electronic calculating machine capable of delivering calculated results by impulses, of a device for tracing curves relative to the calculations performed by said machine and comprising: an electronic stage totalizer of a capacity of (B^n-1) , B being the basis of the numeration system according to which said machine operates, means connecting said electronic totalizer to said machine for receiving the output of said machine for registering the results delivered by said machine as impulses, a rotative registering cylinder, a sensitive paper

on the external surface of said registering cylinder, a driving motor for said registering cylinder, a cylindrical drum fast with said registering cylinder, the lateral surface of said drum being constituted on one part of its periphery with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, means connected to the output of the last stage of said totalizer and being operable thereby to impress said sensitive paper every time that an output impulse is delivered by said totalizer, a support for said means mounted for displacement, in a direction parallel to the axis of said registering cylinder, and a constant amount for each rotation of said registering cylinder, an electronic device controlled by an impulse delivered by said machine, a one revolution clutch between said driving motor and said registering cylinder and being controlled by said electronic device, and means for zeroizing said totalizer at the end of each revolution turn of said registering cylinder.

9. The combination with an electronic calculating machine capable of delivering calculated results by impulses, of a device for tracing curves relative to the calculations performed by said machine and comprising: an electronic stage totalizer of a capacity of (B^n-1) , B being the basis of the numeration system according to which said machine operates, means connecting said electronic totalizer to said machine for receiving the output of said machine for registering the results delivered by said machine as impulses, a rotative registering cylinder, a sensitive paper on the external surface of said registering cylinder, a driving motor for said registering cylinder, a cylindrical drum fast with said registering cylinder, the lateral surface of said drum being

constituted on one part of its periphery with a surface presenting alternatively translucent and opaque sections, said translucent sections being in number B^n , the remaining part of the periphery of said lateral surface of said drum presenting an opaque surface, a luminous supply source and a photoelectric cell facing each other and being respectively in fixed locations on either side of the wall of said drum, an amplifier-generator of impulses so connecting said photoelectric cell with said totalizer that the impulses generated by the amplifier-generator are added to said impulses delivered by said machine to said totalizer, means connected to the output of the last stage of said totalizer and being operable thereby to impress said sensitive paper every time that an output impulse is delivered by said totalizer, a support for said means mounted for displacement, in a direction parallel to the axis of said registering cylinder, and a constant quantity for each rotation of said registering cylinder, means to control and limit to one turn the rotation of said registering cylinder each time a result is supplied by said machine to said totalizer, an opaque disc keyed on the shaft of said registering cylinder, a window in said opaque disc the angular position of which is the same as that of said opaque surface constituting one part of said drum fast with said registering cylinder, a second luminous supply source and a second photoelectric cell facing each other and being respectively on either side of said disc and located in fixed points, devices for zeroizing said totalizer, and an amplifier-generator of impulses connecting said second photoelectric cell to said zeroizing devices.
